UNITED STATES PATENT OFFICE.

JOSEPH ALBERT FORAND, OF PLESSISVILLE, QUEBEC, CANADA.

METHOD OF MAKING RADIATORS.

Application filed December 19, 1924. Serial No. 757,004.

The present invention relates to improvements in radiators and the method of making radiators of the type having inner and outer tubes, and the main object is to provide a most hermetic and resistant joint at the meeting ends of said tubes as well as to reduce the cost of manufacturing same.

The invention will now be fully described in the following specification and is illustrated in the accompanying drawings in which:—

Figure 1 is a vertical sectional view through a radiator section according to the invention.

15 Figure 2 is a cross section on line 2—2 of Fig. 1.

Figure 3 is a longitudinal sectional view through one of the inner tubes.

Referring to the drawings, 1 is the outer wall of a radiator section, each end being open, the inner walls of which are provided with inwardly projecting circumferential flanges 2 and 3 respectively which are then suitably machined or ground, the flanges 28 3 located preferably in the upper end of said radiator section being of larger diameter than the flanges 2.

The inner tubes 4 are also provided at each end, on their outer side, with circumferential flanges 5 and 6 which are also suitably machined or ground respectively, the flanges 5 located at the upper end being preferably of slightly larger diameter than the flanges 6, in order to fit snugly in corresponding flanges 3, the object being to facilitate the entry of the lower flanges 6 through the upper flanges 3.

The lower flanges 6 are preferably provided with tapered outer edges 7, so that 40 when the tubes 4 are inserted in the outer casing 1 they will immediately be centered when they reach the lower flanges 2.

When assembling the outer casing 1 and tubes 4, the outer casing is suitably held in fixed position, and the inner tube 4 first inserted and the lower flange 6 is suitably centered in the adjoining flange 2. Then any suitable pressure is used, such as by means of a press, to force the snugly fitting 50 flanged ends of the inner tubes into the accordingly flanged inner ends of the outer

casing 1. Thus a perfect hermetic joint is obtained.

The proper method to follow to make a radiator of this character is to first cast the outer casing and inner tubes, after which the inner side of the flanges 2 and 3 are suitably machined in their proper size. The flanges of the inner tube are then machined, the flanges 6 being ground to a larger diameter than the flanges 5, in order as above stated to facilitate their entry through the lower flanges 2. The inner tube 4 is then inserted into the outer casing through first, the flange 2 and then the flange 3 when the flanges 5 and 6 on said inner tube are centered in said flanges 2 and 3, and a suitable pressure is used, such as by means of a press to force the snugly fitting flanges into one another. The diameter of the flanges 5 and 6 should be of approximately 1 to 6 thousandth of an inch larger than that of the flanges 2 and 3, thus insuring a perfect hermetic joint.

What I claim as my invention is:

1. In a radiator construction of the type having an outer casing provided with aligned openings and a tube extending through the casing and secured at its ends in said openings, the method of securing the tube in the casing which comprises providing an inwardly directed flange on the casing surrounding one of said openings, suitably machining the inner surface of said flange to a predetermined inner diameter, providing a second flange surrounding the other opening in said casing and suitably machining the inner surface of the same to a predetermined inner diameter smaller than the predetermined inner diameter of said first named flange, providing an outwardly directed flange on one end of said tube and machining the same to a diameter which will enable the same to be inserted through the first named opening in said casing and to a diameter slightly larger than the predetermined diameter of the aforementioned second flange, providing an outwardly directed flange on the other end of said tube and machining the same to a diameter slightly larger than the diameter of said first named flange on the casing,

2
whereby the tube may be inserted in said casing and its flanges brought into engagement with the corresponding flanges on said casing, and forcibly pressing said tube into the casing to bring the flanges of the tube and the flanges of the casing into close contact.

2. A method as specified in claim 1, which includes forming a taper on the inserted end of said tube, whereby the tube 10 is centered in said second named flange.

Signed at Plessisville this 8th day of November, 1924.

JOSEPH ALBERT FORAND.
